UNITED STATES PATENT OFFICE.

GEORGE STIEFEL, OF CHICAGO, ILLINOIS, ASSIGNOR TO GEO. STIEFEL CO., A CORPORATION OF ILLINOIS.

BUNG-CLOSURE FOR BARRELS.

1,068,185.

Specification of Letters Patent.

Patented July 22, 1913.

Application filed August 8, 1911. Serial No. 643,002.

To all whom it may concern:

Be it known that I, GEORGE STIEFEL, a subject of the Emperor of Germany, and residing at Chicago, in the county of Cook and State of Illinois, have invented a new and useful Improvement in Bung-Closures for Barrels, of which the following is a complete specification.

The main objects of this invention are to provide a bung closure for barrels by means of which a draw-off pipe can be quickly attached to or detached from the barrel; to provide a bung closure for barrels which is capable of being quickly opened or closed when it is desired to insert or remove the pipe; to provide a bung closure for barrels which will effectually prevent the escape of gas from the barrel; and to provide a cheap, simple and durable construction which is easy of operation and not liable to get out of repair.

A specific embodiment of the invention is illustrated in the accompanying drawings, in which:

25 Figure 1 is a vertical section of a bung closure embodied in this invention. Fig. 2 is a plan view of the casing with the gas connection removed. Fig. 3 is a plan view of the closure plate. Fig. 4 is a side elevation of the plate. Fig. 5 is a plan view of the operating arm. Fig. 6 is a side elevation of the arm. Fig. 7 is a fragmentary plan view of the bottom cap. Fig. 8 is a side elevation of said cap.

35 In the construction shown, the casing 1 is cylindrical in shape and is provided with external screw threads 2 adapted to be screwed into the bung hole of the barrel. The lower end of the casing is slightly reduced in external diameter and having threaded engagement thereon is the bottom cap 3. Said cap is provided in its bottom, near one side thereof, with a pipe aperture 4 surrounding which, on the inner side of the cap, is a raised seat 5, and at one side of said seat is a raised portion 6 on a level with the seat. Rotatively mounted on said seat 5 and raised portion 6 is a circular closure plate 7 which is of a diameter to fit closely 50 to the walls of the casing, and is provided

with an aperture 8 of the same size as the aperture 4 and positioned near to one side of the plate, or eccentric with the plate, so that when the plate is in one position the aperture 8 will register with the aperture 4. 55

The casing is provided with a circular partition 9 which provides a chamber 10 at one side of the casing in axial alinement with the aperture 4 in the bottom of the cap 3. Said partition extends downwardly 60 in the casing to near the bottom cap and a web or false bottom 11 extends from the bottom of the partition outwardly from the chamber 10 to the walls of the casing.

The chamber 10 is cylindrical and is provided with an annular rib or ledge 12, and an operating arm 13 for the closure plate 7 lies on said plate and has at one end an annular boss 14 which projects up into the chamber and bears on the under side of the 65 flange. The boss 14 has an angular aperture 15 therethrough in axial alinement with the aperture 4, and in the opposite end of the arm is a slot 16 adapted to receive a pin 17 on the plate 7, and near one side thereof. 75

Extending into the chamber 10 is the gas connection 18 which comprises a sleeve 19 having an angular lower end 20 adapted to fit into the aperture 15 to swing the arm 13. The sleeve is provided with a flange 21 between which and the flange 12 is a gasket 22 adapted to close the passage between the sleeve and the casing, and above said flange 21 are lugs 23 adapted to enter notches 24 in the opposite sides of the chamber 10 to 85 a point beneath inclined ledges 25 on the walls of the chamber, and when the sleeve is rotated to move the lugs beneath said ledges the flange 21 is forced down tightly onto the gasket. 90

Opening into the side of the sleeve 19 is a tubular arm 26 adapted to have a rubber hose leading from a source of gas supply attached thereto. The draw-off pipe 27 is adapted to extend down through the sleeve 95 and through the plate 7 into the barrel when the aperture 8 is in register with the aperture 4, and is of less diameter than said sleeve and apertures so that a passage for the gas is afforded about the same to the 100

barrel. On the upper end of the sleeve 19 is a suitable gland 28 adapted to close the opening in the sleeve about the pipe.

The operation of the construction shown is as follows: The casing 1 is secured in the bung hole of the barrel with the closure plate 7 turned in a position to bring its aperture 8 out of register with the aperture 4 in the bottom, as shown in dotted lines 10 in Fig. 2. The sleeve 19 is then inserted into the chamber 10 with its end 20 extending into the aperture 15 of the boss 14. When the sleeve 19 is rotated to move the lugs 23 beneath the ledges 25 the outer 15 end of the arm 13 is swung to the right in Fig. 2, thereby causing the plate 7 to revolve and bring the aperture 8 into register with apertures 4 and 15, in which position the pipe 27 may be forced into the 20 barrel. The gland 28 is then tightened about the pipe and the gas can enter the barrel through the gas fitting 18 and force the contents of the barrel out through the pipe 27. When it is desired to disconnect 25 the pipe from the barrel its lower end is withdrawn into the top of the sleeve 19 and when the sleeve is rotated to release it from the casing, the plate 7 is turned back to close the aperture 4.

30 While but one specific embodiment of the invention has been herein shown and described it will be understood that many details of the construction shown may be varied or omitted without departing from 35 the scope of the claims.

I claim:

1. A bung closure for barrels, comprising a casing having an eccentrically disposed chamber therein and an aperture in 40 its bottom in axial alignment with the chamber, a rotative plate in the chamber having an aperture adapted to be brought into register with the aperture in the bottom of the casing, an arm pivotally connected with 45 said plate, and a sleeve adapted to extend into the chamber and connect with said arm above the rotative plate and when rotated to bring the aperture in the plate into and out of register with the aperture in the 50 bottom.

2. A bung closure for barrels, comprising a casing having an aperture in the bottom thereof near one side of the casing, a partition in the casing providing a chamber 55 in axial alignment with said aperture, a rotative plate in the bottom of the casing having an aperture therein adapted to register with the aperture in the bottom of the casing, an arm pivotally connected with 60 said plate and having an aperture in axial alignment with the aperture in the casing, a sleeve rotatively mounted in the chamber and connected in the aperture in said arm above the rotative plate and adapted when 65 rotated to rotate the plate and move its

aperture into and out of register with the aperture in the bottom, and coacting means on the sleeve and chamber adapted to lock the sleeve in the chamber when said apertures are in register.

3. A bung closure for barrels, comprising a casing having a cylindrical chamber therein at one side of its center, a bottom on the casing having an aperture beneath the chamber, a plate rotatively mounted on 70 the bottom and having an aperture therethrough adapted to be brought into register with the aperture in the bottom, an arm having an apertured boss at one end rotatively mounted in the bottom of the chamber and pivotally connected at its other end with said plate, a rotative sleeve adapted to extend into the chamber and connect in said boss above the rotative plate, interlocking means on the sleeve and chamber, and means 75 adapted to secure a pipe in said sleeve.

4. A bung closure for barrels, comprising a casing, a curved partition providing a chamber at one side of the casing and extending to near the bottom of the casing, a false bottom connecting the bottom of the partition with the walls of the casing, a bottom secured on the casing and having an aperture beneath said chamber, a rotative plate mounted on said bottom and having 80 an aperture therethrough adapted to be brought into register with the aperture in the bottom, an arm having an apertured boss on one end journaled in the bottom of the chamber and having its outer end projecting beneath said ledge and pivotally connected with the plate at one side thereof, a sleeve projecting into the chamber and non-rotatively secured in said boss above the rotative plate, there being means on the 85 sleeve and chamber adapted, when the sleeve is rotated in a direction to bring the plate aperture into register with the bottom aperture, to lock the sleeve in the chamber, and a gland on the outer end of said sleeve 90 adapted to form a tight joint about a pipe 95 passing through the closure.

5. A bung closure for barrels, comprising a casing, means providing a chamber at one side of the casing, a bottom on the casing having an aperture in register with the chamber, a rotative closure in the casing having an off-centered aperture adapted to register with the aperture in the bottom when the closure is in one position, a pipe 105 sleeve rotatively mounted in the chamber above said closure, and means connecting said sleeve and closure adapted when the sleeve is rotated to bring the aperture in the closure into and out of register with 110 the aperture in the bottom.

6. A bung closure consisting of a casing having an eccentric opening and adapted to be secured in a barrel opening, a closure plate in said casing having an eccentric 115

opening registrable with the casing opening and a fluid conduit sleeve disposed in alignment with the casing opening above the closure plate, and having movable connection with said plate to bring the same into and out of closure position thereunder.

In witness whereof I have hereunto sub-

scribed my name in the presence of two witnesses.

GEORGE STIEFEL.
